UNITED STATES PATENT OFFICE.

ABNER D. STRONG, OF ASHTABULA, OHIO.

WATER ELEVATING AND DISTRIBUTING SYSTEM.

No. 832,930.

Specification of Letters Patent.

Patented Oct. 9, 1906.

Application filed June 10, 1905. Serial No. 264,702.

To all whom it may concern:

Be it known that I, ABNER D. STRONG, a citizen of the United States, residing at Ashtabula, in the county of Ashtabula and State 5 of Ohio, have invented certain new and useful Improvements in Water Elevating and Distributing Systems, of which the following is a specification.

This invention is designed chiefly as an improvement on the system for which Letters Patent of the United States were granted me October 29, 1901, No. 685,495, the purpose being to enable the compressed-air inlet and the air-outlet of the water reservoir or tank 15 to be controlled from any room or convenient place at one operation and to obviate the annoyance and inconvenience occasioned by having to wait for the water-tank to fill or receive a charge should it be found empty 20 when attempting to draw water from any of the outlets of the service-pipe.

For a full description of the invention and the merits thereof and also to acquire a knowledge of the details of construction of the 25 means for effecting the result reference is to be had to the following description and accompanying drawings.

While the invention may be adapted to different forms and conditions by changes in 30 the structure and minor details without departing from the spirit or essential features thereof, still the preferred embodiments are shown in the accompanying drawings, in which—

35 Figure 1 is a perspective view of an apparatus embodying the invention. Fig. 2 is a detail view of the valve mechanism. Fig. 3 is a detail perspective view of a modification showing two water reservoirs or tanks and 40 duplex valve mechanisms. Fig. 4 is a detail perspective view of the duplex valve mechanism.

Corresponding and like parts are referred to in the following description and indicated 45 in all the views of the drawings by the same reference characters.

Figs. 1 and 2 show an arrangement of the devices coöperating with a single reservoir or tank, whereas Figs. 3 and 4 show two tanks 50 or reservoirs and coöperating parts, whereby when one tank is wholly or in part empty the supply of water is drawn from the other tank, thereby enabling the empty tank to be filled without causing any annoyance or inconven-

ience to the person desiring to draw water 55 from an outlet of the service-pipe.

In the construction shown in Fig. 1, A indicates an air-compressor of any construction either to be operated by hand or in any desired way. A reservoir B is connected by pipe b with the compressor, so as to be charged thereby. The water reservoir or tank C is closed and receives a supply of water from a suitable source by means of pipe D, provided with the usual check-valve d. The 65 service-pipe E is connected with the reservoir or tank C and conveys water to the different rooms or other required point of use.

A pipe 1 enters the reservoir or tank C and connects at one end with a valve 2, whose 70 opposite end is connected by pipe 3 with the compressed-air reservoir B. A pipe 4, in communication with the upper portion of the tank C, is connected at its upper end with a valve 5, the opposite end of said valve having 75 communication with the air to provide an escape for the air confined in the tank C displaced by the water flowing therein through the pipe D. The valve-stems of the valves 2 and 5 are connected to a lever 6, fulcrumed between its ends to a standard 7, projected upward from a framework 8, supporting the valve mechanism. A weight 9 is 80 slideable upon the lever 6 and causes depression of one or the other end of said lever 85 6, whereby the supply of water to the tank C and the discharge of water from said tank are controlled. For convenience in the operation of the weight 9 a cord or rope 10 is provided, the same having positive connection 90 with the weight 9 and passing around a guide-pulley 11 at one end of the lever 6 and having its portions passed around guide-pulleys 12 and extended to a convenient point or points for operation. In this connection it 95 is to be understood that the operating-cord 10 may have branches leading to the different rooms of a dwelling or to any other convenient point, so that the person desiring to obtain a supply of water may operate the weight 9 to 100 permit the tank C to be recharged or to receive a supply of compressed air, as may be required.

The reservoir B is charged with air under pressure, and a regulator 13 controls the supply to the pipe 3, and consequently to the tank C. When the tank C is charged, the valve 5 is closed and the valve 2 opened.

Hence the water confined in the tank C is acted upon by pressure, and in the event of any outlet of the service-pipe E being opened the water flows freely therefrom, as will be readily understood. When the tank C becomes empty or it is required to replenish the same, the weight 9 is moved upon the lever 6 to cause said lever to assume a reverse position, whereby the valve 2 is closed and the valve 5 opened. This permits the water to pass freely from the source of supply through the pipe D into the tank C, the displaced air finding a ready outlet through the pipe 4 and valve 5. After the tank C has been replenished or sufficiently charged the weight 9 is moved toward the opposite end of the lever 6, thereby causing the valve 5 to close and the valve 2 to open, thereby restoring the parts to a normal working condition.

In the construction shown in Figs. 3 and 4 two water tanks or reservoirs B and B' are provided and are connected in such a manner as to admit of the one being charged, while the other is adapted to supply the water drawn from the service-pipe E. A branch D' connects the tanks, and the supply-pipe D is coupled thereto, check-valves being interposed in the arms of said branch between the connection of the pipe D therewith and the respective tanks. A branch E' similarly connects the service-pipe E with each of the tanks B and B', and its arms are provided with check-valves e, which operate in alternation similarly to the check-valves d. Two sets of valves 2 and 5 are required, and the pipes 3, leading from one end of the valves 2, connect with a head F, to which the pipe 3 from the compressed-air reservoir B^a connects. A valve f controls communication between each pipe 3 and the head F, thereby admitting of either one of the sets of valves and tank B or B' being cut out. The stems of corresponding valves 2 and 5 are connected by levers 6, and said levers are coupled, by means of tie-rods 14, to move in unison. A beam 15 is mounted upon the tie-rods 14 to oscillate with the levers 6, the whole constituting a pivoted frame or structure. The weight 9 is slidably mounted upon the beam 15 and is controlled by an operating cord or rope 10, passed around guide-pulleys 11 and 12 in the manner stated. When the weight 9 is moved toward one end of the pivoted frame, the valves 2 and 5 at the corresponding end are opened, thereby venting the tank B' and shutting off the vent and supply of water to the tank B and opening the supply of compressed air thereto. Upon opening any outlet of the service-pipe E the water is drawn from the tank B. When the tank B is in circuit, the tank B' is out of circuit and receiving a supply. When it is required to recharge the tank B, the weight 9 is shifted to the opposite end of the pivoted frame, there-

by closing the valves 2 and 5, coöperating with the tank B', and opening the valves in coöperating relation with the tank B, thereby cutting the tank B out of circuit and throwing the tank B' in circuit, so that the water may be drawn from the tank B' upon opening an outlet of the service-pipe during the time that the tank B is out of circuit and replenishing. The provision of the two tanks B and B' and the duplex set of valves enables water to be drawn at all times without necessitating waiting for the tank to be charged in the event of it being found empty when it is required to draw water therefrom. The shifting of the weight from one end of the pivoted frame or lever to the other simultaneously vents the tank and shuts off the supply of compressed air or closes the vent and opens the valve controlling the supply of compressed air to the tank.

In my previous system, herein noted, two operations were required, and failure to properly operate the two sets of valves would result in inoperativeness of the apparatus. Moreover, the operating cord or rope provides convenient means for controlling the valves from any selected or desired point.

Having thus described the invention, what is claimed as new is—

1. In a water elevating and distributing system, the combination of an air-tight tank, a valved pipe for automatically supplying water to the tank when the internal pressure is relieved, a valve-controlled vent having connection with the upper portion of the said tank, a valve-controlled compressed-air-supply pipe having connection with the lower portion of said tank, a lever fulcrumed between its ends and having the valves of both the vent and compressed-air supply connected, respectively, to opposite ends, and a weight movable upon the lever from one side of its fulcrum to the other to simultaneously operate both valves of the vent and compressed-air supply, whereby the one is opened and the other closed and vice versa.

2. In a water elevating and distributing system, the combination of separate water-tanks, each adapted to receive a supply of water, a vent and a compressed-air pipe connected with each tank, separate valve mechanisms for the vent and compressed-air pipes of said tanks, and a shifting weight adapted to be controlled from a remote point for simultaneously operating the valve mechanisms whereby one of the tanks is cut out of circuit to be replenished, while the other tank is brought into circuit for supplying water as required.

3. In a water elevating and distributing system, the combination of tanks for receiving a supply of water, valved connections between said tanks, a vent and a compressed-air pipe for each of said tanks, separate sets

of controlling-valves for the vent and compressed-air pipes, a pivoted frame or lever having the stems of said valves connected therewith, and a shifting weight adapted to be controlled from a remote point to effect simultaneous operation of the valves to admit of throwing one of the tanks into circuit and the other out of circuit, whereby one tank

may be charged while water is drawn from the other tank.

In testimony whereof I affix my signature in presence of two witnesses.
